WINDOW BLIND

Carl V. Bergstrom, Santa Monica, Calif.

Application April 10, 1948, Serial No. 20,259

8 Claims. (Cl. 160—166)

1

The invention relates to window blinds.

The general object of the invention is to provide a window blind which may be used in place of the more complicated, more expensive and less easily cleaned Venetian blind.

A further object of the invention is to provide an all metal blind of simple and inexpensive construction in which the louvers are integral with or rigidly connected to longitudinally extending corrugated strip members which on contraction or expansion will move the louvers to open or closed position.

A further object of the invention is to provide in a blind of the character above described means for rendering a portion of the blind inoperative while allowing another portion to be opened and closed.

A further object of the invention is to provide a blind of the character described which may be operated from either the top or bottom of the window.

A further object of the invention is to provide a blind of the character described in which the louvers may be so connected as to be moved in one instance to a closed position on the stretching of the anchoring means and in another instance to an open position when said anchoring means is stretched.

The invention further consists in the several features hereinafter described and more particularly defined by claims at the conclusion hereof.

In the drawings:

Fig. 1 is a composite front elevation view of a blind embodying the invention in which the left hand half of the figure shows the blind in an open position and the right hand half of the figure shows the blind in a closed position;

Fig. 2 is detailed elevation view of the upper portion of a blind embodying the invention provided with means for operating the same from the top of the blind;

Fig. 3 is a composite view of a blind embodying the invention in which the right and left hand halves of the blind are similar to Fig. 1 and illustrating how only a portion of the blind may be opened and closed;

Fig. 4 is an enlarged composite elevation view of a portion of a blind embodying the invention, the left hand half showing the blind in an open position and the right hand half showing the blind in a closed position;

Fig. 5 is a detailed vertical sectional view taken on the line 5—5 of Fig. 4;

Fig. 6 is a detailed vertical sectional view taken on the line 6—6 of Fig. 4;

2

Fig. 7 is an enlarged composite elevation view of a portion of a blind embodying the invention in which the left hand half is in a closed position and the right hand half is in an open position;

Fig. 8 is a detailed vertical sectional view taken on the line 8—8 of Fig. 7;

Fig. 9 is a detailed vertical sectional view taken on the line 9—9 of Fig. 7;

10 Fig. 10 is a detailed vertical sectional view taken on the line 10—10 of Fig. 4.

Referring to Figs. 1 to 6 of the drawings, the numeral 12 designates a window frame and 13 the window in front of which my improved blind is mounted.

15 The improved blind comprises a marginal metal frame having top and bottom portions 14 and 15 and corrugated side portions 16. Between the top and bottom portions of the frame 20 and anchored to the side portions 16 are a plurality of louvers 17. As shown in the above figures, the whole blind is formed from a single sheet of suitable sheet metal, such as a suitable aluminum alloy, which is subjected to punch 25 pressing operations to slit it transversely at spaced distances to form the louvers and to form the corrugations 18 in the side portions of said sheet, so that after the pressing operation, the louvers 17 extend at an angle to the corrugated side portions as shown in Fig. 5 and are in an 30 open position, so that when a stretching pressure is imposed on the side portions 16 by pulling outwardly on one end of the sheet, the louvers 17 will assume the closed position shown in Fig. 6. The sheet may, as shown in Fig. 1, 35 be anchored at its top portion 14 by screws 19 to the upper portion of the window and be normally held in an open position by studs 20 that engage in holes 21 in the bottom portion 15 as shown at the left hand halves of Figs. 1 and 3 40 and be held in an open position by disengaging it or slipping it off the studs 20 and pulling it down until the holes 21 may be slipped over studs 22 on the window frame 12 as shown at the right hand halves of Figs. 1 and 3 or conversely 45 the sheet may be anchored at its bottom portion 15 to the window frame and moved and held in its different positions by cords 23 secured to the top portion 14 extending over guides 24 on the window frame and connected to a handle member 25 provided with a series of notches 26, as shown in Fig. 2, any one of which may engage with a stud (not shown) secured to the window frame.

50 Where only partial operation of the blind is desired, the blind may be anchored to the window frame.

55

dow frame midway of its length, for example, as shown in Fig. 3 by screws 27 securing its upper half to the window frame as shown in Fig. 3.

Where the blind is very wide, the louvers may be connected intermediate their ends by rivets 28, spot welding, or in other suitable manner to one or more longitudinally extending corrugated strips 29 as shown in Figs. 4 and 10, or where it is not desired to form the blind in one piece, separate metal sheets may be used to form the louvers 17 and strips, similar to the strips 29, may form the sides of the blind frame and carry the louvers as shown in Fig. 10, so that when these strips are flexed, the louvers will be moved to a closed position as shown in Fig. 6.

Instead of pressing or connecting the louvers to their corrugated carrying strips so that they are in an open position in the unstretched condition of the corrugated side strips, they may, as shown in Fig. 8, be disposed to assume a closed position and to move to an open position as shown in Fig. 9 when the corrugated side portions are stretched. Where the corrugated strips are separate, they may be formed of a different metal from the louvers, for example, flat spring steel strips.

It is to be noted that so long as the marginal corrugated side strips or portions 16 are properly anchored at one end, the transverse portion 14 or 15 at this anchored end is not absolutely essential.

From the above it will be noted that I have provided a blind of simple and inexpensive construction and one which may be easily cleaned either by a vacuum cleaning or by taking it down and washing it with a pressure spray.

It is also to be noted that while the corrugated part of the blind may be metal, it is not necessarily limited thereto as any suitable material such as a plastic or rubber composition which has the requisite spring tension may be used in the corrugated part of the blind.

I desire it to be understood that this invention is not to be limited to any particular form or arrangement of parts except in so far as such limitations are included in the claims.

What I claim as my invention is:

1. In a window blind, the combination with marginal contractible and expandible corrugated side strips of flexible metal, of a series of spaced louvers anchored to said strips between the crests of the corrugations of said strips and movable by said strips to different positions on the stretching or contraction of said strips.

2. A window blind in accordance with claim 1 wherein a corrugated strip is secured to the louvers intermediate their ends.

3. A window blind in accordance with claim 1 wherein the corrugated strips and the louvers are integrally connected.

4. A window blind in accordance with claim 1 wherein the corrugated strips are rigidly attached to the louvers.

10 5. A window blind in accordance with claim 1 wherein the louvers extend laterally at an obtuse angle to the sides of the corrugations of said strips in their open position when said side strips are contracted and extend at an acute angle to the sides of the corrugations of said strips in their closed position when said side strips are stretched.

20 6. A window blind in accordance with claim 1 wherein the louvers extend at an acute angle to the sides of the corrugations of said strips in their closed position when said side strips are contracted and extend laterally at an obtuse angle to the sides of the corrugations of said strips in their open position when said side strips are stretched.

7. In a window blind, the combination with a window frame of marginal corrugated side strips of resilient metal anchored at one of their ends to said frame, a series of spaced louvers anchored to said strips between the crests of their corrugations, and means for anchoring the other ends of said strips to said frame in stretched and unstretched condition.

30 8. A window blind in accordance with claim 7 wherein the side strips are also anchored at an intermediate point to the frame so that only a portion of the blind is adapted to be moved on the stretching and unstretching of the strips from one end of said frame.

CARL V. BERGSTROM.
